RAZOR BLADE RECEPTACLE

Pat R. Breazeale, Jacksonville, Fla.

Application June 27, 1951, Serial No. 233,870

3 Claims. (Cl. 30—40)

My invention relates to razor blade receptacles, and more particularly to receptacles positionable on a razor of the blade injection type to receive automatically the used blade upon ejection from the razor, and further relates to combinations of injection razors, used blade receptacles and new blade magazines.

A general object of my invention is to eliminate the exposure of the cutting edge of blades during the replacement of blades in a razor.

Another object of my invention is to provide a simple and inexpensive used blade receptacle for use with blade injector type razors which will make unnecessary any manual handling of used blades.

A further object of my invention is to provide a cardboard or similar carton for packaging a clip or magazine of new blades which will function as a used blade receptacle after removal of the clip therefrom.

An additional object is to minimize the possibility of used blades falling from an entrance opening in a used blade receptacle.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawings in which Fig. 1 is a perspective view of a new blade magazine, a razor and a receptacle in accord with my invention in disassembled aligned positions; Fig. 2 is a perspective view of the devices of Fig. 1 assembled for use in replacing the blade in a razor and automatically disposing of the used blade as ejected from the razor; Fig. 3 is a perspective view of a clip and receptacle in accord with my invention coupled together as it is contemplated they will be stored between active uses thereof in replacing and receiving blades; Fig. 4 is a perspective view of a carton for a new blade magazine in accord with my invention; Fig. 5 is a detail view of an end of a receptacle in accord with a modification of my invention; Fig. 6 is a sectional view of a receptacle in accord with my invention showing an arrangement applicable to a type of carton differing slightly from the carton of Figs. 1 through 3; Figs. 7 and 8 are perspective views disclosing another modified receptacle in accord with my invention; Fig. 9 is a plan view of a carton blank to form a carton in accord with Fig. 4; and Fig. 10 is a perspective view of a magazine carton which may serve without alteration as a used blade receptacle in accord with my invention.

Fig. 1 of the drawings shows a razor 1, as now perfected, approximately in accord with the U. S. patent to O. V. Rodrigues, No. 1,969,945, entitled "Razor and Loading Device Therefor," and a clip or magazine 2, as now perfected, holding new blades for the razor which is approximately in accord with the U. S. patent to L. Kuhn, No. 2,043,046, entitled "Magazine for Razor Blade." My invention is not directed to such razor or magazine, per se, but contemplates a receptacle particularly adapted for

2

use with razors and magazines of this general type, and my invention further contemplates combinations including such razors and magazines. It will be understood that various modifications may be made to adapt the receptacle herein described to types of injector razors other than that shown, as well as to other types of blade magazines, and the underlying principles of my invention are generally applicable to injector razors and blade magazines. The term injector razor as used herein, accordingly, refers to razors in which the blade may be slidably ejected from the razor by, or at the same time as, a new blade is being inserted thereto, while the term injector magazine, or injector clip, refers to any mechanism or arrangement for injecting a new blade into an injector razor in such manner that the used blade is automatically or at the same time ejected therefrom.

In accord with the preferred embodiment, as shown in Fig. 1, the used blade receptacle comprises an elongated rectangular box-like body portion 3 closed at a back end 20 by suitable flaps 4 and partially closed at the front or entering end by a single flap 5 extending upwardly from the bottom toward the top of the container but being short enough to leave an opening 6 in the form of a slot extending transversely across the upper portion of the front face and serving to admit used blades upon ejection from the head of razor 1. One side of the receptacle protrudes as a tab 7 which serves to connect the receptacle to the razor during replacement of the blade. The tab is proportioned to fit within the channel 8 in the razor head in much the same manner as key 9 of the magazine 2 is inserted. Since tab 7 is to be inserted in this channel, and since the razor head will normally be of metal, while the receptacle will preferably be made of cardboard or other inexpensive and soft material for economy, though harder and stronger materials would otherwise be preferred, it may be necessary or desirable to impregnate the tab 7 and more or less of the receptacle adjoining the tab with a hardening or stiffening material. Synthetic resin glues, animal glues, or waxes may be employed for this purpose, for example, and it is to be understood that the reinforcement of the tab 7 in this manner may comprise a thorough impregnation or a mere layer of bonding agent between the overlapped layers of the receptacle material, or an external coating or layer on the tab or a portion 40 thereof.

The tab 7 is shown as formed on the side of the receptacle on which the edges of the blank are overlapped and, usually, glued together. This construction is preferred when the receptacle material has a thickness about one-half that of the key 9. For thicker material, it may be preferable to join the edges of the blank at the side opposite the tab 7, whereby the tab will be of single thickness.

A generally square aperture 10 and two slits to form 55 a short strap 11 are cut in the top of the receptacle as shown in Fig. 1 for purposes hereinafter considered in connection with Fig. 3.

Referring now to Fig. 2, the clip 2 is positioned with key 9 in place in the razor head channel to deliver or inject 60 a new blade into the razor, and the used blade receptacle is in position on the razor with tab 7 in the opposite end of the channel to receive the ejected used blade. The key 9 is first inserted into the razor head channel to spread the channel by moving a portion of the razor head against leaf spring 12. This enlargement or opening of the channel by the metal key 9 before insertion of tab 7 reduces wear on the tab of softer material and permits the tab to fit snugly in the channel wherein it is held sufficiently firmly to stay in place primarily by friction, aided in some degree by the pressure of spring 12 under some circumstances depending upon the tab thickness, the key thickness, and the condition of the razor.

As seen in Fig. 2, the slider 13 of the magazine 2 has just been brought forward to inject a new blade into the razor in the manner described in the above identified patents and the used blade 14 has just left the razor head, has passed freely through the slot 6 and is falling freely into the receptacle 3. This blade will come to rest on the bottom 15 of the receptacle and will not interfere with the entrance later on of other used blades. As shown in Fig. 2, the flap 16 at the closed rearward end of the receptacle is inserted along the top of the receptacle, and in order that the entering blade 14 will not become lodged above the flap, the tab 7 is formed to hold the receptacle body at a slight angle to the razor head. This angle may not be necessary or desired if the flap 16 is arranged to extend along the bottom 15 instead of along the top. The elimination of the angle is further considered below in connection with Fig. 6.

Upon completion of the blade replacing operation in accord with Fig. 2, the tab 7 is first removed from the razor head, and then the key 9 of clip 2 is also removed to free the razor of appendages and leave it ready for use.

In order that the used blade or blades in the receptacle will not fall out through slot 6, it being understood that flap 5 effectively covers or encloses the end of the receptacle except for this slot, the key 9 of the clip is inserted as shown in Fig. 3 along the outer top of the receptacle body under strap 11, and the small protrusion 17 of the key enters the rectangular opening identified as opening 10 in Fig. 1. In this position, the body of the blade clip 2 abuts the flap at the receiving end of the receptacle and closes the blade-entering slot above the flap. When the clip and receptacle are connected in this manner, used blades are effectively trapped in the hollow body of the receptacle 3, while the receptacle and clip are retained together ready for the next blade replacement. The closing of the slot by the clip body need not be complete, but the slot should be sufficiently covered to prevent the passage of one of the blades.

The used blade receptacle is conveniently made from the carton in which the clip of new blades is sold. Fig. 4 shows a complete carton in the form of an elongated rectangular box, of which the overall length is sufficient to accommodate the clip including its key. The carton is arranged for parting along a rouletted, partially cut or otherwise weakened parting line 18a near the central portion of the carton, the rearward portion forming the receptacle 3, while the forward portion 18 may be discarded. The parting line 18a extends around the carton, as is apparent in Fig. 4, in a manner to leave the tab 7 and flap 5 attached to the receptacle, and to facilitate proper parting of the carton, these parts may be completely, or substantially completely, cut out by the cuts on line 18a, while the cuts across the top and far side are less complete. The rectangular aperture 10 and strap 11 of the receptacle are formed in the carton for use as described in connection with Fig. 3. If desired, the aperture 10 may not be completely cut through in the carton, but may be partially cut and arranged to accept the small hook-like protrusion of the key by removing from the path of the protrusion material loosely held in the aperture.

There may be a tendency for the blades being expelled from the razor head to catch upon the end of the slot of the receptacle adjacent the back edge of the blade. This tendency can be overcome by the provision, as shown in Fig. 5, of a crimp 18 at the base of tab 7, which will offset tab 7 from the side of the receptacle. The entering blade will then be spaced slightly from the wall portion 19 which forms the back end of the slot 6 above flap 5. In order that the crimp 18 will be retained in the material of which the carton, and receptacle, are made, particularly if this material is cardboard, the glue holding the overlapped edges of the carton together at the back side, and throughout the tab 7, may possess a reinforcing

and strengthening characteristic which opposes bending after setting of the glue. The crimp 18 may be maintained by other means, of course, such as by the inherent characteristic of many types of cardboard, or other materials of which the receptacle could be formed, to retain a crimp once firmly made, or by the use of synthetic resin impregnation of the tab 7, or by the insertion of a thin sheet of plastic or metal possessing some degree of stiffness as a reinforcing member between the overlapping edges of the carton.

There is less tendency for the entering blade to catch at 19, as shown in Fig. 5, if the receptacle edges overlap in the direction shown in Fig. 1 rather than as shown in Fig. 5. Thus it may be desired, particularly when the crimp 18 is to be omitted, to overlap the edges by bringing the downwardly extending edge attached to the top of the receptacle over and outside of the upwardly extending edge attached to the bottom of the receptacle, this being the construction shown in Fig. 1.

In Figs. 1-5 as discussed above, the tab for insertion into the slot of the razor head has been shown and described as extending upwardly at a small angle, and, as further explained, this angle is intended so to position the receptacle on the razor head that an entering blade will not follow the top of the receptacle and become lodged between the upper receptacle wall and an inserted closing flap. If the closing flap 20, as seen in Fig. 6, however is tucked in along the bottom 15 of the receptacle, the angle may be omitted and the tab 7 may extend straight out from the body of the receptacle in accord with Fig. 6. Blades entering slot 6 will then fall upon the top of the tucked-in portion of flap 20 and will not tend to work out of the back end of the receptacle. It is to be understood that the tab angle discussed immediately above may be provided or omitted, in accord with Fig. 1 or Fig. 6 as desired, and that the direction selected does not necessarily effect the desirability of providing the offsetting crimp shown in and discussed in connection with Fig. 5.

A modified tab construction is shown in Figs. 7 and 8, wherein a member 21 of metal, plastic, wood, fiberboard, or the like, is affixed, by gluing, stapling, crimping or otherwise, to the inside of the back wall 22 of the receptacle. The member extends outwardly from the receptacle at the entrance end to form a tab portion 23 and a locking finger 24. As seen in Fig. 7, the forward end of a carton may have been torn off and discarded to leave the receptacle body 3, tab 23, finger 24, and flap 5. To prepare the receptacle for use in receiving used blades, the flap 5 is bent upwardly to leave an entrance slot 6 as shown in Fig. 8, and the finger 24 is bent over against the flap 5 to hold it in the upwardly extending position across the open end.

In constructions where the tab comprises a readily formed material, an elongated knob or guide protrusion 25 is preferably provided to engage in a portion of the channel in the razor head in the manner in which the similar guide protrusion of the key of the new blade clip engages therein at the other end of the head. It may be desirable to form such knob even if the nature of the material of the tab requires that a separate piece of material be glued in place to comprise the knob. This knob tends to guide the tab into the razor head channel into a specific predetermined position and locates the receptacle with greater precision in respect to the head, thus reducing the chance of misalignment. The knob 25 further serves to increase the frictional forces tending to hold the tab in the razor channel. To hold reasonably securely in the channel, the tab 23 should have approximately the same thickness as the key of the new blade clip. This thickness may be the thickness of the metal or other material employed for the tab 23, or, for example, a layer of the carton material may extend alongside the tab portion 23 provided by the attached member 21. Other means for

providing this thickness will occur to those skilled in the art.

Fig. 9 discloses a plan of a carton blank for forming a carton in accord with Fig. 4, from which the receptacle of Fig. 1 may be formed. Line 18a represents a broken knife cut, rouletting or other weakened portion across the carton. The carton is formed from the blank in any desired manner, by folding along longitudinal dashed lines 26, and preferably folding the edge portion 27 inside of edge portion 28 to reduce the chance of the blade catching at the end of its entrance slot in the receptacle. After the completed carton has been used in connection with the sale of the new blade clip which it is proportioned to house, it is broken at line 18a as explained in connection with Fig. 4, whereby the portion lying to the right of line 18a in Fig. 9 becomes the receptacle for used blades.

While Figs. 1-9 of the drawings are directed to a receptacle for used blades formed by tearing away a portion of the clip carton, the whole carton may be employed as a receptacle. Fig. 10 is a view of a combined carton and receptacle arranged to enclose the body of a clip of new blades but to permit the key thereof to protrude alongside tab 29. The rearward end of the carton is closed by flaps 30, as in the earlier described constructions of Fig. 2 or of Fig. 6, for example, and these flaps are opened to remove the clip and are closed again thereafter. Two flaps 31 and 32 partially close the forward end of the carton and are preferably glued together. A blade entering slot 33 remains above the cross flap 31 and the upwardly extending flap 32, and while these flaps may meet the lower portion of tab 29, a cut out portion 34 is provided at the upper corners of the flaps near the tab through which the key of the clip may extend. The resultant position of the key tends to reinforce the tab 29 during the time before the clip is removed for use to prevent damage to the tab during shipment.

The construction of tab 29 in Fig. 10 differs from that of any of the other figures and comprises a three layer upper portion and a two layer lower portion. The tab is so cut that an extended ear 35 of cardboard protrudes from the end of the tab-forming portion of the outer layer of the receptacle. This extended ear is then folded over at 36 back against the inner side of the inner layer of the tab, terminating just inside the receptacle at 37. The ear is glued against the inner side of the tab, and reinforces the tab at the base, where the tab joins the body of the receptacle. The bend at 36 tends to prevent fraying of the end of the tab, particularly if the cardboard of which the receptacle is made is of the type having a cast coated or similar glazed surface. The three layer upper portion of the tab will fit snugly in the upper portion of the razor channel when this portion of the channel has been opened by insertion of the key of the new blade clip, in the opposite end. As seen in Fig. 10, the end of the razor channel has an upper portion 38 which is somewhat wider than the lower portion 39, when the key is in place, and as taught in the above patent to Rodrigues, No. 1,969,945, the blade 40 is released from a clamping action by this expansion of the upper portion of the channel. The tab 29 thus conforms generally to the shape of the channel, and it is held in alignment by the thick upper portion of the tab. A further slight advantage is obtained by this construction, in that the increased amount of material applied to the inner side of the tab moves the end of slot 33 further from the path of the blade, tending thereby to perform the function of the crimp in the tab considered above in connection with Fig. 5.

After removal of the clip from the carton of Fig. 10 as described, the carton is used as a receptacle in the manner suggested in Figs. 2 and 3. A rectangular aperture 10 and strap 11 are provided to permit the attachment of the clip to the receptacle as in Fig. 3, and it is to be noted that the aperture and strap are positioned in respect to the slot 33 and the tab end of the receptacle of Fig. 10

as they are in Figs. 1-9. The receptacle of Fig. 10 may be, of course, of greater overall length than the receptacles of Figs. 1-9 in that the body of a clip which is to be housed in the body of the receptacle of Fig. 10 is of greater length than an individual blade. While the tab 29 of the device of Fig. 10 is shown aligned with the body of the receptacle as in Fig. 6, it will be understood that the tab may be at an angle as in Figs. 1-4 and it may be reinforced by stiff glue or plastic impregnation or otherwise. The tab as shown in Fig. 10 is particularly well adapted for use when the whole carton is to be the used blade receptacle, but other tabs may be provided in this instance, and the construction of tab 29 can be used with a rouleotted dividable carton similar to that of Fig. 4 if desired. The ear 35 of tab 29 tends to perform the function of knob 25 of Figs. 7 and 8, and both will probably not be found desirable.

Reference numerals have been applied to several figures of the drawings not discussed specifically in connection therewith, such numerals being provided to correspond and relate to parts described in connection with other figures.

The operation of the devices is believed clear from the descriptions hereinabove. The carton in each case protects the new blade magazine after manufacture thereof until the magazine has been sold and is to be used. The carton may, of course, be printed and colored to form an attractive display container, and directions for use may also be printed thereon. After removal of the blade magazine through the recloseable flaps at one end, the carton of Fig. 4 is parted along the parting line as described and the receptacle portion retained for use. In the construction of Fig. 10, the flaps 30 are opened to permit withdrawal of the magazine. Thereafter the magazine key may be inserted into the channel of the razor head, the tab of the used blade receptacle inserted in the other end of the channel to dispose the blade entrance slot or opening in alignment to receive the ejected used blade, the magazine operated to force a new blade into the razor and thereby to eject the old blade directly from the razor into the receptacle, and the receptacle and magazine thereafter detached from the razor. In order conveniently to have the magazine and receptacle stored together to be immediately available when next to be used, and in order that the blade entrance slot may be closed against the accidental falling out of the used blade, the magazine is attached to the receptacle, by means of strap 11 and aperture 10, from which it is readily detachable for subsequent use.

When the operation of replacing blades has been completed a sufficient number of times to empty the magazine, it is intended that the magazine should be attached to the receptacle as shown in Fig. 3 and that both should be discarded. Either or both may be reused, however, if desired, and the used blades in the receptacle may be emptied out preferably by opening the flaps at the rearward end.

If is preferred for reasons of economy that the carton and receptacle of my invention should be fashioned of inexpensive fibrous sheet material, such as cardboard, but it may be desired to make a more attractive, sturdier or longer lasting receptacle from metal or molded plastic, or other materials. It will be understood that the rearward end flap of the receptacle may be inserted along the top as shown by flap 16 in Fig. 2, or along the bottom as shown by flap 29 in Fig. 6, primarily in accord with the shape and disposition of the magazine in the carton. The device of Fig. 10 is described as having a hollow body portion sufficiently long to house only the magazine body, but it may be desired to house the whole magazine including the key thereof. In the latter instance, the tab 29 may be bent over against flaps 31 and 32 and straightened out into the position perpendicular to this end of the carton at the time of use of the carton as a used blade receptacle, and in

this case, it may further be desired to form the tab of metal which will better withstand such bending. It will further be understood that more than two or three thicknesses or layers of material may be provided in the tab as determined by the thickness of the particular material and the extended width of the razor channel. Accordingly, while I have shown certain preferred embodiments of my invention by way of illustration, other modifications will occur to those skilled in the art and I therefore wish to have it understood that I intend, in the appended claims, to cover all such modifications as fall within the true spirit and scope of my invention.

What I claim as new and desire to secure by Letters Patent of the United States is:

1. A used blade receptacle comprising a hollow blade-containing portion open at an end, a flap partially closing said end and defining a blade entrance slot in said end, a protruding injector-razor-channel-engaging tab extending outwardly from the plane of said end adapted and arranged to dispose said slot to receive a used blade ejected from an engaged razor, and an injector-magazine-key-receiving member on said blade-containing portion adapted and arranged to retain an injector magazine detachably in covering relation to said slot. 15
2. A used blade receptacle comprising a hollow body portion having a side wall and having an end slot for receiving used blades, said slot being adjacent said side wall, a laterally extending strap on said side wall, said side wall having an aperture, a key removably inserted 20
- 25

under said strap along said side wall, a protrusion from said key removably engaged in said aperture, and a body member attached to said key and extending in covering relation to said slot.

- 5
3. A used blade receptacle comprising a hollow body portion having a side wall and having an end slot for receiving used blades, said slot being adjacent said side wall, a laterally extending strap on said side wall, said side wall having an aperture, a key removably inserted under said strap along said side wall, a protrusion from said key removably engaged in said aperture, and a body member attached to said key and extending in covering relation to said slot, said key and body member constituting a new blade injector magazine.
